Primary Examiner—James M. Gandy*Assistant Examiner*—Pamela Burgess*Attorney, Agent, or Firm*—H. Jay Spiegel[57] **CLAIM**

The ornamental design for a set of lottery cards, as shown and described.

DESCRIPTION

FIG. 1 is a front elevational view of a set of lottery cards showing my new design; and,

FIG. 2 is a rear elevational view thereof.

It is understood that the claimed design is of conventional thickness.
